UNITED STATES PATENT OFFICE.

WILLIAM R. SCHMIDT, OF BEEMER, NEBRASKA.

FIREWOOD SPLITTING MACHINE.

Application filed May 17, 1927. Serial No. 192,094.

This invention relates to machines for splitting wood and particularly to machines for splitting fire wood and including a power operated reciprocating axe and means 5 for supporting the wood to be split in advance of the axe.

The general object of the present invention is to provide a machine of this character having means whereby it may be arranged to accommodate fire wood of different lengths and a further object is to provide means whereby a block may be interposed between the back stop which normally supports the billet of wood which is to be split, 10 and the billet itself so as to permit shorter pieces of wood to be split without having to adjust the back stop, this block being movable into position by means of a treadle.

Other objects have to do with the details 20 of construction and arrangement of parts, these being such as to permit the devices to be readily handled, to permit the logs or billets to be readily adjusted in advance of the axe, and permit the machine as a whole to 25 be readily transported.

My invention is illustrated in the accompanying drawings, wherein:

Figure 1 is a top plan view of a wood splitting machine constructed in accordance 30 with my invention, the cylinder and piston being in section;

Figure 2 is a longitudinal sectional view of the machine;

Figure 3 is a top plan view of the rear 35 portion of the frame with the platform removed;

Figure 4 is a section on the line 4-4 of Figure 3;

Figure 5 is a fragmentary perspective 40 view of a portion of the platform;

Figure 6 is a perspective view of the auxiliary back stop.

Referring to these drawings, it will be seen that the machine generally speaking 45 consists of the longitudinal beams 10 having the front wheels 11, the rear wheels 12 and the tongue 13 whereby the machine may be transported from place to place. Mounted upon a bed 14 carried upon the beams 10 is 50 a tubular guide which may be circular in cross section or rectangular in cross section as desired, this guide 15 being illustrated as rectangular in cross section and extending longitudinally of the beams 10 and open at both ends. Mounted upon the beams 10 is 55 the transverse crank shaft 16 carrying the

relatively heavy fly wheels 17. One of these fly wheels carries upon it a pulley 18 whereby power may be transmitted to the shaft 16 from any suitable source of power by means 60 of a belt for instance. Operating within the guide 15 is the body or axe supporting slide 19, which may be of any suitable construction and which fits the guide 15 just as a piston fits a cylinder. This is provided 65 with the wrist pin 20 and a connecting rod 21 of any suitable construction connects this slide with the crank shaft 16. The axe 22 is carried by the body 19, the axe being adapted to be engaged with this slide in any suitable 70 manner as for instance by welding. The axe has the usual form. Obviously, of course, the axe will reciprocate in the guide as the crank shaft rotates.

Attached to the longitudinal beams 10 is 75 an approximately U-shaped frame composed of the longitudinal members 23 and the cross member 24. This may be made of strap iron, angle iron or any other suitable element. The irons 23 are formed with a plurality of perforations or bolt openings 25 and the beams 10 are also formed with like perforations, the perforations 25 of the members 23 being disposed at uniform distances apart and the corresponding perforations of the beams 10 being disposed also at uniform distances apart so that the frame formed of the members 23 and 24 may be adjusted 80 longitudinally upon the members 10 and then bolted in place. Supported upon the rear ends of the beams 10 and upon the frame formed of the members 23 and 24 is the transversely extending platform 26 which is composed of one or more planks 85 over which the axe operates. Attached to the transverse member 24 is the back stop 27. This is preferably made of steel bolted, riveted, or otherwise attached to the member 24 and is preferably about one inch thick, twelve inches wide and eight inches high or rather it projects above the members 24 about eight inches. The platform 26 is preferably hollowed out where the log will be disposed immediately in front of the back stop. Extending across the frames formed 90 of the members 23 and 24 and engaged therewith in any suitable manner is a brace 28 and pivotally mounted upon this brace for vertical movement are the arms 29 which arms carry a wooden block 30 disposed immediately in front of the back stop 27. The block 30 is bolted to the arms 29 by belts 31 95 100 105 110

which extend vertically downward through the block and the arms 29 are connected by a cross rod 32. Also pivoted upon the brace 28 is the treadle 33 which extends out in front of the machine in such a position that the operator may readily use it and this treadle 33 is connected by a chain 34 to the transverse brace 32, this chain passing over a pulley 35 mounted under the platform 26. Thus it will be seen that when the treadle is depressed the arms 29 will be pulled upward and the block 30 will be brought into position immediately in advance of the back stop 27. When the pressure on the treadle is relieved, the weight of the block 30 will cause the depression of the arms 29 to a position where the upper face of the block 30 will be in alinement with the upper faces of the planks 26. The upper face of this block 30 also is formed with a slight depression or valley. In order to keep this block up in case for any reason a succession of relatively short billets of wood are to be split, the block is provided with a transverse opening 36 through which a pin may be passed, this pin being adapted to rest upon the upper edges of the platform 26 so as to support the block in position. This pin is readily removed in case the block is not desired to be in more or less constant use.

In the use of this mechanism it will be understood, that the frame composed of the members 23 and 24 is longitudinally adjusted upon the beams 10 to suit the particular length of wood which is standard in the community where the machine is to be used. Different communities usually have certain standard lengths of logs or billets of wood and thus the frame which carries the back stop may be set away from the cutting edge of the axe a distance sufficient to accommodate this standard length of wood. Each time the axe is retracted the operator removes the split billet of wood and places a new billet upon the platform and against the back stop 27 and the axe in its forward movement strikes the end of this billet and splits it. In case the operator should see that a relatively short billet of wood is coming to be split he can immediately step upon the treadle 33, lifting the block 30 upward which block is from four to six inches in thickness and this accommodates the relatively short billet which is then split in the usual manner. If for any reason the wood is running short in length, so that there are many pieces to be successively presented to the axe which are within the standard length, the block 30 may be held raised by a pin inserted in the opening 36 as before stated. Preferably the axe has a sixteen inch or greater stroke and preferably the fly wheels will be not less than forty inches in diameter. The pulley 18 has a diameter of about thirty-six inches. This pulley or band

wheel may be attached to the fly wheel in any suitable manner.

This fire wood splitter permits the splitting of fire wood when green or dry and permits the splitting of wood blocks which ordinarily are not split because of the hard labor necessitated in splitting them by hand. Using green wood increases the fuel value of the wood about forty percent. The machine splits more wood with two or three men operating the machine than ten men with a hand axe. It may be remarked that my machine has been used in splitting cord wood and splitting fire wood for a large community and that eighteen cords of wood were split in one day by three men of the community. The machine will split blocks as large as can be lifted on to the platform and without regard as to whether the wood is tough or not. The slide guide or housing 15 for the axe being tubular absolutely prevents the axe from getting out of place and holds the axe to the work without regard to the toughness of the work so that the axe cannot be deflected. If for any reason the axe cannot enter the block of wood or cannot split it, the belt will either fly off or slide. This usually indicates that the block has been placed cross-wise but the flying off of the belt or the slipping of the belt will, of course, prevent the machine from being broken. The large fly wheels are particularly essential as they give steadiness and power to the axe. The machine may be run with a four horse power gas engine, but even without the aid of an engine if the fly wheels be given a few turns by hand, a billet of ash or elm twenty-four inches in diameter and eighteen inches long may be split twice. One of the special advantages of my invention resides in the use of these relatively large fly wheels which give power and steadiness to the axe. By using a large pulley I gain power and at the same time reduce the speed at which the slitter operates as obviously the axe should not reciprocate rapidly. This large pulley 18 permits any engine to be used without too much strain upon it. In the use of this machine, preferably one man places the blocks on the platform, another one stands in front of the axe and operates the treadle, while another man receives the pieces and throws them aside into the pile.

I claim:

1. A machine for splitting wood comprising a supporting frame, a longitudinally extending tubular guide housing mounted upon the frame, a slide fitting said guide housing and reciprocating therein and carrying an axe, a crank shaft mounted upon the supporting frame and operatively connected to said slide, a pair of heavy and relatively large fly wheels mounted upon the shaft, a pulley mounted upon the shaft, a belt en-

gaging the pulley whereby power may be transmitted to the shaft, a frame adjustable upon the main frame longitudinally thereof and carrying a back stop, and a supporting platform mounted upon said last named frame in front of the back stop.

2. A machine for splitting wood comprising a supporting frame, a longitudinally extending guide housing mounted upon the frame, a slide fitting said guide housing and reciprocating therein and carrying an axe, a crank shaft mounted upon the supporting frame and operatively connected to said slide, a pair of heavy and relatively large fly wheels mounted upon the shaft and having means whereby power may be transmitted to them, a frame adjustable upon the main frame longitudinally thereof and carrying a back stop, a block shiftable into place between the back stop and the axe and adapted to compensate for relatively short billets.

3. A machine for splitting wood comprising a supporting frame, a longitudinally extending guide housing mounted upon the frame, a slide fitting said guide housing and reciprocating therein and carrying an axe, a crank shaft mounted upon the supporting frame and operatively connected to said slide, a pair of heavy and relatively large fly wheels mounted upon the shaft and having means whereby power may be transmitted to them, a frame adjustable upon the main frame longitudinally thereof and carrying a back stop, a block shiftable into place between the back stop and the axe,

arms pivoted upon the second named frame for vertical movement and carrying said block, and a treadle operatively connected upon said arms and upon depression acting to shift the block into position in front of the back stop.

4. In a wood splitting machine, a reciprocating axe, power operated means for reciprocating the axe, a back stop, and a block adapted to be disposed in front of the back stop to compensate for relatively short logs, treadle operated means for raising or lowering the block, and means for holding the block in a raised position independent of the treadle.

5. A machine for splitting wood including a main wheel supported frame, a longitudinally extending guide housing mounted on the frame, a slide fitting said guide housing and reciprocatable therein, and carrying an axe, power operated means for reciprocating said slide and including a fly wheel, an auxiliary U-shaped frame having sliding engagement with the main frame, means for permitting the auxiliary frame to be longitudinally adjusted upon the main frame and for holding it in its adjusted position, a stop carried by the auxiliary frame at the end thereof, and opposed to the axe, a block insertible into position between the stop and the axe, pivoted arms supporting said block, and manually operable means for raising the block or lowering it including a treadle.

In testimony whereof I hereunto affix my signature.

WILLIAM R. SCHMIDT.
